REVERSING AND SPEED-REGULATING MECHANISM FOR STEAM ENGINES

Application filed July 5, 1927. Serial No. 203,482.

My invention relates to reversing and speed regulating mechanism for steam engines and more particularly to an improvement in means of controlling volume of flow and distribution of steam to the engine for reversing direction or varying the speed of operation.

In accomplishing this object I have provided improved details of structure, the preferred forms of which are illustrated in the accompanying drawings, wherein:

Fig. 1 is a plan view of a single cylinder, horizontal steam engine equipped with my improved reversing and speed-regulating mechanism, a part of the cylinder and valve

shafts being broken away for better illustration.

Fig. 2 is a vertical section on the line 2—2, Fig. 1.

Fig. 3 is an enlarged detail perspective view of the reversing and speed-regulating mechanism.

Fig. 4 is a transverse vertical section on the line 4—4, Fig. 6.

Fig. 5 is a vertical section on the line 5—5, Fig. 1.

Fig. 6 is a vertical section on the line 6—6, Fig. 1.

Referring more in detail to the drawings: 1 designates the body casting of a steam engine of horizontal type comprising a base 2, crank shaft bearings 3—3', a cross head guide 4, a cylinder head flange 5 and valve rod guides 6 all of conventional design. 7 designates a cylinder having a flange 8 attached to the head flange 5 on the body casting by bolts, to mount the cylinder rigidly on the body casting.

Located within the cylinder chamber 10 is a piston 11 having a rod 12 extended through the inner cylinder head and operatively connected with the pin 13 of the main crank shaft 14 through a connecting rod 15. The bearings 3—3' are of the usual split construction and the crank shaft 14 provided with a fly wheel 16.

The valve chest 17 formed integrally with the cylinder 6 comprises a chamber 18 having communication with opposite ends of the cylinder chamber 10 through the ports 19 and 20 and is provided with the usual intermediate exhaust port 21. Located within the valve chest is a slide valve 22 adapted for selectively communicating the steam chamber with either end of the cylinder chamber through a port 19 or 20 and simultaneously communicating the opposite end of the cylinder chamber with exhaust port 21 through the opposite intake port 19 or 20 in accordance with common practice.

The steam valve 22 is provided with a rod 23 which extends rearwardly through a stuffing box 24 into and through the guide 6 where it is provided with an angular section 25 for properly guiding the rod during its reciprocatory movement. At its rear end the valve rod 23 is pivotally connected with the connecting rod 26 operable synchronously with the crank shaft through the improved gearing mechanism which I will now describe.

27 designates a bracket comprising an inside, vertical plate 28 attached, adjacent the crank shaft, to the side of the engine casting, preferably by bolts 29, and provided near its lower edge with an outwardly directed shelf 30 having a standard 31 extending parallel with and in spaced relation to the attaching plate 28. An outside plate 32 lying parallel with and in spaced relation to the standard 31 is attached to the shelf 30, preferably by the bolts 33. The inside plate 28 and the standard 31 are provided with paired bearings 34 and 35, and rotatable in said bearings are the extended hub portions 36 and 37 of a gear wheel 38 which meshes with a gear wheel 39 fixed on the crank shaft 14.

The gear wheel 38 and its extended hub portions 36 and 37 are provided with an interior spiral groove 40 for the spiralled rib 42 of a contained sleeve 43 which constitutes the sleeve of an elongated worm gear wheel.

Extending through and keyed to the sleeve or worm gear wheel 43 by splines 44 is a secondary shaft 45, having a reduced end 46 journaled in the bearing 47 on the upper end 5 of the inside plate 28 of the bracket 27, and forming a shoulder 48 for abutment against the inner face of the bearing to limit longitudinal movement of the secondary shaft.

Fixed to the reduced portion 46 of the shaft 10 45 is a crank 49 which is adapted for bearing laterally against the face of the adjacent bearing 47 to limit longitudinal movement of the shaft in the opposite direction and provided with an eccentric pin 50 on which the 15 head 51 of the valve connecting rod 26 is pivotally mounted.

Fixed to the outer end of the sleeve or elongated worm gear wheel 43, preferably by a set screw 52, is a stop collar 53. Fixed on 20 the opposite end of said sleeve or elongated worm gear wheel, preferably by a set screw 54, is a collar 55 having an annular, peripheral groove 56 receiving the clutch segments 57 having studs 57' projecting through openings 25 58 of a yoke 59 of a lever 60 which is pivotally mounted on a pin 61 carried by the ears 62 that project inwardly from the inside bracket plate 28; the end of the lever opposite the yoke being provided with a handle 63 whereby the 30 lever may be shifted on its pivotal mounting to shift the collar 55. The collars 53 and 55 may be spaced to provide for movement of the worm gear wheel within its gear wheel 38 from one given extreme to the other before 35 interruption of movement by contact with either of the collars at a relative end of the bearings 34 and 35, or the collars may be set to interrupt movement of the wheel at intermediate points.

40 Assuming the parts to be constructed and assembled as described, and further assuming, for illustration, that adjustments of the valve are made with the crank on dead center, the operation is as follows:

45 For normal forward operation of the engine the valve controlling crank is set perpendicularly above its shaft with the crank slightly below its rearward dead center. As the crank shafts revolve, the valve regulating 50 crank moves forwardly in front of the main crank, opening the forward valve port to admit steam to the rear portion of the piston chamber to drive the piston forwardly and rotate the crank clockwise (Fig. 1). With 55 the valve regulating crank set perpendicularly below its shaft, and the main crank slightly above dead center, the valve crank will lead the main crank on reverse operation.

60 Position of the valve regulating crank in line with the main crank would neutralize the valve operation and prevent admission of steam to either end of the piston chamber, while any adjustment intermediate the neutral position and either extreme would serve 65 to advance or retard admission of steam to

the cylinder and correspondingly vary the power and speed of the engine.

In order to effect adjustment of the valve regulating crank for either forward or reverse operation of the engine and for intermediate speeds, the elongated worm gear is shifted longitudinally by means of the operating lever, the toothed connection between the elongated sleeve 42 and the gear wheel 38 effecting rotation of the sleeve and the 70 secondary shaft because of the locked engagement of the gear wheel 38 with the gear wheel on the main crank shaft with which it is in mesh, and rotation of the secondary shaft shifting the valve regulating crank to 75 vary its angularity relative to the main crank shaft. The stop collars on the elongated worm gear or toothed sleeve may be so spaced that when the gear or sleeve is at one limit of its movement, the valve regulating crank is set for maximum forward operation of the engine and when at the other limit of its movement, for maximum reverse travel.

80 Intermediate speeds may be secured by adjustment of the collars on the sleeve at points intermediate the extremes so that when the sleeve is shifted in one direction a collar will engage a hub of the worm gear wheel before its extreme is reached and thereby limit angularity of the valve crank and resultant opening of the valve port.

85 It is apparent therefore that the worm gear mechanism may be set to provide desired speed of operation and that when a setting is made the operation for forward or reverse travel may be controlled by shifting of the control lever to contact one or the other of the collars with the hub of the inner gear wheel and limit shift of the sleeve in direction of thrust.

90 Other changes to meet requirements of different engine structure may be made without departing from the spirit of my invention.

95 What I claim and desire to secure by Letters Patent is:

1. A reversing and speed regulating device for steam engines including in combination with a crank shaft, a steam valve and a valve rod, a secondary shaft, a crank on the secondary shaft connected with the valve rod, a sleeve splined on the secondary shaft and slidably longitudinally thereon, the sleeve having external threads, a drive wheel threaded on said sleeve, the sleeve being movable through the drive wheel, means driving the drive wheel from the crank shaft, and means for shifting the sleeve longitudinally to effect rotation of the sleeve through its threaded connection with the relatively stationary drive wheel for varying angularity of the valve rod crank including a clutch member engaged with the sleeve.

100 2. A reversing and speed regulating device for steam engines including in combination with a crank shaft, a steam valve and a valve
